(57) **CLAIM**

The ornamental design for the cutlery, as shown and
described.

DESCRIPTION

FIG. 1 is a top, left, front perspective view of the first
embodiment of the cutlery.

FIG. 2 is a bottom, left, rear perspective view of the first
embodiment of the cutlery.

FIG. 3 is a rear, end view of the first embodiment of the
cutlery.

FIG. 4 is a front, end view of the first embodiment of the
cutlery.

FIG. 5 is a top view of the first embodiment of the cutlery.

FIG. 6 is a left, side view of the first embodiment of the
cutlery.

FIG. 7 is bottom view of the first embodiment of the cutlery.

FIG. 8 is a right, side view of the first embodiment of the
cutlery.

FIG. 9 is a top, left, front perspective view of the second
embodiment of the cutlery.

FIG. 10 is a bottom, left, rear perspective view of the second
embodiment of the cutlery.

FIG. 11 is a rear, end view of the second embodiment of the
cutlery.

FIG. 12 is a front, end view of the second embodiment of the
cutlery.

FIG. 13 is top view of the second embodiment of the cutlery.

FIG. 14 is a left, side view of the second embodiment of the
cutlery.

FIG. 15 is a bottom view of the second embodiment of the
cutlery.

FIG. 16 is a right, side view of the second embodiment of the
cutlery.

FIG. 17 is a top, left, front perspective view of the third
embodiment of the cutlery.

FIG. 18 is a bottom, left, rear perspective view of the third
embodiment of the cutlery.

FIG. 19 is a rear, end view of the third embodiment of the
cutlery.

FIG. 20 is a front, end view of the third embodiment of the
cutlery.

FIG. 21 is a top view of the third embodiment of the cutlery.
(Continued)

FIG. 22 is a left, side view of the third embodiment of the cutlery.

FIG. 23 is a bottom view of the third embodiment of the cutlery; and,

FIG. 24 is a right, side view of the third embodiment of the cutlery.

The broken lines shown illustrate portions of the cutlery and form no part of the claimed design.
